UNITED STATES PATENT OFFICE.

JAMES L. EAMES, JR., OF MILLVILLE, NEW JERSEY.

ASH-RECEPTACLE.

1,184,331.

Specification of Letters Patent. Patented May 23, 1916.

Application filed April 12, 1915. Serial No. 20,882.

To all whom it may concern:

Be it known that I, JAMES L. EAMES, Jr., a citizen of the United States, residing at Millville, in the county of Cumberland and State of New Jersey, have invented certain new and useful Improvements in Ash-Receptacles, of which the following is a specification.

My invention relates to improvements in ash receptacles, and more particularly to an improved attachment for chair arms or other articles of furniture, the object of the invention being to provide an ash receptacle which is normally hid from view, but which may be readily moved into position to receive the ashes whenever desired.

A further object is to provide an ash receptacle of the character stated which may be conveniently attached to the arm of a chair or other similar piece of furniture, which will be extremely small and inexpensive in construction, and which will not disfigure the piece of furniture, but rather enhance its general appearance.

A further object is to provide an ash receptacle of the character stated with improved means for moving the same from its exposed to its hidden position, and vice versa, and which means is in convenient reach of the operator seated in the chair.

With these and other objects in view, the invention consists in certain novel features of construction and combinations and arrangements of parts as will be more fully hereinafter described and pointed out in the claims.

In the accompanying drawings: Figure 1 is a fragmentary plan view of a chair arm illustrating my improved attachment thereon. Fig. 2 is an inverted plan view of the chair arm shown in Fig. 1, but illustrating the ash receptacle in its hidden position. Fig. 3 is a view in longitudinal section on the line 3—3 of Fig. 2.

1 represents a support which we will assume to be the arm of a chair, and to the under face of the arm, my improved attachment is secured.

2 is a metal plate which is secured by 50 nails or screws 3 to the bottom of the chair arm, and to which plate 2, a frame 4 is pivotally connected by means of a rivet 5 or other suitable connecting means.

The frame 4 constitutes a flat plate having a rectangular opening 6 therein to receive the removable ash receptacle 7. The

receptacle 7 conforms in shape to the shape of the opening 6, and is provided at its upper edge with flanges 8 resting on the frame 4, and supporting the tray. 60

When the frame 4 is in its closed or hidden position, the open upper end of the receptacle 7 will be closed by the plate 2, and there will be no danger of the ashes sifting out upon the floor. 65

A curved bar 9 is pivotally connected at one end as shown at 10 to the frame 4 adjacent the pivot 5 of the latter, and between its ends is provided with a curved slot 11 through which a stud 12 on plate 2 projects. 70

The free end of the bar 9 is bent forming a finger hold 13, which is located in convenient reach of the occupant of the chair, and by the manipulation of the bar 9, the frame 4 may be swung outwardly to the position shown in Fig. 1, or may be returned to the hidden position under the chair as shown in Fig. 2. 75

The stud 12, in slot 11, limits the pivotal movement of the frame 4 in both directions, 80 and also operates to a certain extent as a brake to prevent the frame 4 from accidental movement in either direction.

When it is desired to empty the receptacle 7, it can be readily lifted out of the hole 6 in frame 4, and after it is cleaned, can be returned to position. 85

While I have described what I believe to be a preferred embodiment of my invention and a practical use of the same, I would 90 have it understood that I do not limit myself to the precise details of construction, nor to the precise use indicated, as my improved device is capable of a wide range of usefulness in private and public places, hospitals and sanitariums, in smoking cars of trains, and in many other places. 95

I therefore consider myself at liberty to use the attachment for any use for which it is capable, and consider myself at liberty 100 to make such changes and alterations as fairly fall within the spirit and scope of the appended claims.

Having thus described my invention, what I claim as new and desire to secure 105 by Letters Patent is:

1. An attachment of the character described, comprising a plate, a receptacle supporting frame pivotally connected to the plate, and an operating bar pivotally connected to the frame, said bar having a slot 110 therein, and a stud on the plate projected

into the slot in the bar, substantially as described.

2. An attachment of the character described, comprising a plate, a receptacle supporting frame pivotally connected to the plate, an operating bar pivotally connected to the frame, said bar having a slot therein, a stud on the plate projected into the slot in the bar, said stud limiting the movement 10 of the frame in both directions, and said bar

having an operating finger at its free end, substantially as described.

In testimony whereof I have signed my name to this specification in the presence of two subscribing witnesses.

JAMES L. EAMES, JR.
